DEVICE FOR INTERNAL COMBUSTION ENGINES

Max Dach, Flushing, N. Y.

Application June 26, 1934, Serial No. 732,409

7 Claims. (Cl. 123—124)

This invention relates to a device to be used in connection with internal combustion engines and is particularly useful when such engines are used for driving motor vehicles. By this invention the maximum speed at which the engine can be run is predetermined and can be varied. If the speed of the engine becomes too high, the vacuum in the intake manifold is broken and the ignition for the engine is cut out or disconnected.

In carrying out the invention an air inlet is provided, preferably with several branches to the inlet manifold of the engine, this air inlet being normally closed by a valve that is opened when the engine reaches a predetermined speed. For this purpose the valve may be connected to the governor of the engine or electrical or hydraulic or other devices can be used to open the valve when the engine reaches a predetermined speed.

Provision is also made so that the rapidity with which the vacuum in the intake manifold is broken can be varied, thus avoiding complete breaking of the vacuum when the engine exceeds the predetermined speed for only a short while.

The air inlet may be provided with branches leading to the atmosphere with a valve in one branch that is closed only when the throttle valve to the engine is opened an appreciable extent and the other branch may be provided with a normally closed valve that can be opened when the speed of the engine approaches the maximum predetermined permissible speed. Provision is also made by means of which an alarm is sounded when the engine reaches its approximate maximum predetermined speed.

The invention will be understood from the description in connection with the accompanying drawing in which Fig. 1 is a side view of an illustrative embodiment of the invention; Fig. 2 is a longitudinal section of a device like that shown in Fig. 1 with certain features added; Fig. 3 is a side view of a modification and Fig. 4 is a plan view of Fig. 3.

In the drawing reference character 1 indicates an air inlet for the intake manifold that is closed at one end and provided with a flange 2 by means of which it may be attached to the engine, or any other convenient support in the vicinity of the intake manifold. The other end of the inlet 1 is open and a plurality of outlets 3 is provided through its walls from which connections 3a are made to a number of places distributed along the intake manifold.

A valve 4 is provided in the inlet 1, this valve being shown as a butterfly type, although other

types of valves may be used. The valve 4 is mounted upon a shaft 5 that extends through air-tight bearings in the side walls of the inlet 1. An arm 6 is connected to one of the outwardly extending ends of the shaft 5 and a connection 7 is pivoted to the end of the arm 6, this connection 7 extending, for example, to the governor of the engine. The valve 4 may be connected in other ways so as to be opened when the engine speed reaches a predetermined value.

A mercury switch 8 is connected to the other outwardly extending end of the shaft 5 and the ignition circuit of the engine, a portion of which is indicated by the wires 9, extends through this switch so that the ignition circuit is opened when the valve 4 opens sufficiently.

In the modification shown in Fig. 2 the inlet 1 is externally threaded, as shown at 10, and a cap 11 is screwed on to the same. The cap 11 is provided with a hole 12 into which a conically shaped closure plug or closure member 13 that is supported on the inlet 10 by means of the spider 14, enters when the cap 11 is adjusted so as to vary the size of the opening for air to enter the inlet 1.

In the modification shown in Figs. 3 and 4 parts like those already described are designated by the same reference characters with primes. In this modification the open end of the inlet 1 is enlarged, as shown at 20, and is provided with two branches 21 and 22.

The branch 21 is shown as being provided with a valve 23 of the butterfly type. This valve is mounted on a shaft 24 that extends through air-tight bearings in the walls of the branch 21. An arm 25 is connected to one of the outwardly extending ends of the shaft 24 and a connection 26 is pivoted to the end of the arm 25. The connection 26 may extend to the throttle of the engine so that when the throttle is opened to a position beyond idling speed the valve 23 is closed. Connections from the throttle of the engine to the valve 23 may be made in any other convenient way to close this valve when the throttle opens.

A valve 27, which may also be of the butterfly type, is provided in the branch 22. This valve is carried by a shaft 28 that extends through air-tight bearings in the walls of the branch 22. An arm 29 is rigidly attached to an extending end of the shaft 28 and a mercury switch 30 is attached to the other extending end of this shaft 28.

An arm 31 is rigidly connected to the outwardly extending end of the shaft 5' opposite the end to which the mercury switch 8' is connected and an adjustable screw 32 is provided near the outer 55

end of the arm 31 in position to contact with the arm 29 when the valve 4' is opened sufficiently.

A whistle or other alarm device 33 that is operated when air passes through the inlet 22 is 5 provided in this inlet.

The outer end of the enlarged portion 20 of the inlet 1' is closed by a plate 35. An opening 36 is provided in this plate preferably between the branches 21 and 22. An air regulator is mounted 10 on the plate 35 above the hole 36. This air regulator comprises an externally threaded cylindrical member 37 surrounding the hole 36 and a conical plug 38 is carried by the spider 39 near the center of the member 37. A cap 40, provided 15 with an opening 41 into which the plug 38 enters, is screwed upon the member 37 and can be adjusted in position to regulate the amount of air that is permitted to pass into the inlet 1' through the hole 36. A connection 42, which leads 20 from an air cleaner or purifier, may be connected to the outer end of the enlarged portion 20 of the inlet.

The operation is as follows:

With the device shown in Fig. 1, when the 25 engine reaches a predetermined maximum speed that may be fixed at different points by setting the governor to which the connection 7 is connected, the valve 4 is opened and the air rushes into the inlet 1 and thence through the openings 30 3 into the inlet manifold, thus breaking the vacuum and causing fuel to cease being fed into the engine. At the same time the switch 8 opens the circuit through the ignition for the engine. This circuit may conveniently be through the 35 primary coil. In the modification shown in Fig. 2 the cap 11 can be so adjusted that there will be a delay before the vacuum is broken or the adjustment may be such that the vacuum is merely reduced instead of being broken when the valve 40 4 is open.

In the device shown in Figs. 3 and 4 the valve 4' opens sufficiently when the speed exceeds the maximum for which the device is set, thus permitting air to enter through the opening 36 45 and reduce or break the vacuum. The valve 23, that is connected to the throttle of the engine, will be open while the engine is running at idling speed, but closes when the throttle is opened to feed fuel to the engine. The valve 27 is normally closed, but opens when the engine speed 50 approaches the maximum for which the device is set due to the fact that a slight opening of the valve 4' causes the screw 32 on the long arm 31 to strike the short arm 29 of the valve 27 and open this valve sufficiently to permit air to pass through the branch 22 and sound the alarm 33, thus warning the operator that he has reached

about the maximum permissible speed and also apprising others that the vehicle is traveling at high speed.

I claim:

1. In a device for the intake manifold of an 5 internal combustion engine, an inlet, a valve in said inlet, and means independent of the suction in the intake manifold to open said valve and break the ignition circuit to said engine when the engine reaches a predetermined speed. 10

2. In a device for the intake manifold of an internal combustion engine into which fuel is caused to flow, an inlet, a valve in said inlet, and means independent of the suction in the intake manifold to open said valve and break the ignition 15 circuit to said engine when the engine reaches a predetermined speed, said means comprising a switch controlled by said valve. 15

3. In a device for the intake manifold of an internal combustion engine, a branched inlet, a 20 valve in said inlet, an air operated alarm in one of the branches, and means to open said first named valve when the engine reaches a predetermined speed. 20

4. In a device for the intake manifold of an 25 internal combustion engine, a branched inlet, a valve in said inlet, a valve in one of the branches which is opened by a predetermined amount of opening of said first named valve, and means independent of the suction in the intake manifold to open said first named valve when the engine reaches a predetermined speed. 30

5. In a device for the intake manifold of an internal combustion engine, a branched inlet, a valve in said inlet, a valve in each one of said 35 branches, and means independent of the suction in the intake manifold to open said first named valve when the engine reaches a predetermined speed. 35

6. In a device for the intake manifold of an 40 internal combustion engine into which fuel is caused to flow, a branched inlet and adjustable means independent of the suction in the intake manifold for admitting various regulated amounts of enough air into said inlet independent of said 45 branches to reduce the vacuum therein sufficiently to cause fuel to cease being fed into the engine. 45

7. In a device for the intake manifold of an internal combustion engine into which fuel is caused to flow, a branched inlet, valves in the 50 branches, and adjustable means independent of the suction in the intake manifold for admitting various regulated amounts of enough air into said inlet independent of said branches to reduce the vacuum therein sufficiently to cause fuel to cease 55 being fed into the engine.

MAX DACH.
